P. B. SAUGEN,
CARBON REMOVING DEVICE,
APPLICATION FILED NOV. 29, 1920.

1,401,499.

Patented Dec. 27, 1921.

UNITED STATES PATENT OFFICE.

PETER B. SAUGEN, OF TACOMA, WASHINGTON.

CARBON-REMOVING DEVICE.

1,401,499.

Specification of Letters Patent. Patented Dec. 27, 1921.

Application filed November 29, 1920. Serial No. 426,896.

To all whom it may concern:

Be it known that I, PETER B. SAUGEN, a citizen of the United States, and resident of the city of Tacoma, county of Pierce, State 5 of Washington, have invented certain new and useful Improvements in Carbon-Removing devices, of which the following is a specification.

My invention relates to improvements in 10 carbon removing devices; more particularly it relates to devices of that character for removing carbon deposits from the walls of cylinders of internal combustion engines.

It is the principal object of the invention 15 to provide a device of the above stated character that is adapted for use in cylinders of various diameters, which can be easily applied and operated and whereby all carbon deposits can be quickly and thoroughly removed from the cylinder walls and from 20 the ends of pistons operating in said cylinders.

It is another object of the invention to 25 provide a carbon removing device comprising a rotatable block wherein a plurality of scraping blades are yieldingly mounted for radial movement and which may, by pressure applied against the block, be actuated to engage the cylinder walls to clean them of 30 carbon as the block is rotated.

Another object of the invention resides 35 in the detail construction of the block, the character of the blades used and the manner in which they are mounted.

In accomplishing these and other objects 40 of the invention, I have provided the improved details of construction, the preferred forms of which are illustrated in the accompanying drawings, wherein—

Figure 1 is a perspective view illustrating the application of a carbon removing device embodying the present invention within the cylinder of an engine; also showing the application of one type of actuating 45 tool thereto.

Fig. 2 is a detail perspective view of the carbon removing tool by itself.

Fig. 3 is a top plan view of the carbon removing device showing in dotted lines, the 50 scraping blades extended.

Fig. 4 is a vertical section taken on the line 4—4 in Fig. 3.

Fig. 5 is a horizontal sectional view taken on the line 5—5 in Fig. 4.

Referring more in detail to the several 55 views of the drawings, wherein like refer-

ence numerals designate the same or like parts—

1 designates a blade supporting block, or head, which is preferably but not necessarily 60 of a triangular form as is shown in Fig. 3, and which is provided centrally on its upper surface with a wrench head 2 whereto a wrench or other socketed tool, as shown at 3 in Fig. 1, may be applied in such manner that 65 through it pressure may be applied to the block while it is being rotated.

Formed within the block, in planes perpendicular to its top surface and radially with respect to a central vertical line, are 70 slots 5, and slidably contained within these slots are scraping blades 6 provided along their outer vertical edges with similarly beveled scraping surfaces 7 and along their lower edges with beveled scraping surfaces 75 8; the edges 8 all lying normally in the same horizontal plane.

The base 10 of the walls of each of the slots 5 is formed on an incline of about 45 degrees, as is shown best in Fig. 4, and extends from the edge of the block at its upper surface to approximately the middle of the block at the lower surface. The inner corner of each of the scraping blades is likewise beveled to engage the inclined 85 bases of their respective slots in such manner that, with the lower edges of the blades seated against a supporting member such as the upper end of a piston, downward movement effected by pressure on the block 90 will cause the blades to be moved radially outward and into engagement with the cylinder walls.

In order that the blades may be held in position and normally retained at their inner 95 limit of travel, I have provided each with an opening 12 wherein collars, or sleeves 13 are fitted. Extending about the block and through the collars 13 is a continuous, spring band 14 which is for the purpose of yieldingly resisting outward movement of the blades and for retracting and normally retaining them within the slots.

Within the vertical edges of the vertex portions of the block I have formed pockets 105 15 for receiving the spring band and collars within the blades, so that these parts may lie within the limits of the block and will in no way interfere with its operation.

Assuming that the different parts are so 110 constructed and assembled, the device would be used in the following manner: For re-

moving carbon deposits from the walls of a cylinder of an automobile engine of the ordinary type, the engine head is first removed to give access to the cylinder, the 5 crank shaft is then turned to properly position the piston within the cylinder so that the scraping tool may be inserted as is shown in Fig. 1, to seat against the piston end. Pressure is then applied downwardly against 10 the block by the use of a tool or wrench as shown at 3, to cause the blades to be actuated outwardly against the cylinder walls, and simultaneously the block is rotated to cause the blade edges 7 to scrape the carbon 15 deposits therefrom, and the edges 8 to clean the piston end. Removal of pressure from against the block permits the spring band to retract the blades within the block so that the device may be removed from the 20 cylinder.

It is apparent that a device of the above character may be applied to cylinders of various diameters, and that being equipped with both horizontal and vertical scraping 25 edges, the cylinder walls and piston ends will be simultaneously cleaned.

It is further apparent that such a device 30 will be very effective, easily operated, will quickly and thoroughly perform its work and can be made at a relatively small cost.

Having thus described my invention, what I claim as new therein and desire to secure by Letters-Patent is—

1. A device of the character described 35 comprising a body block having means thereon for connection with an actuating tool, a plurality of blades slidably mounted in the block and having scraping surfaces at their outside and lower edges which are adapted, 40 when the device is in use, to respectively scrape the inside wall and base of a cylinder, said blades being mounted within the block in such manner that pressure against the block which would tend to force it toward the base of the cylinder, will effect radially 45 expanding pressure against the blades.

2. A carbon removing device of the character described comprising a body block having 50 a plurality of radially directed slots therein, blades slidably mounted within the

said slots and having their outer and lower edges beveled to form scraping surfaces; said lower edges being adapted to lie normally within the same plane and the said outer edges being perpendicular to said plane, means for effecting radial movement of the blades by downward pressure on the block and means on the upper face of the block whereby connection may be made with an actuating tool. 55

3. A carbon removing device of the character described comprising a body block having means thereon for connection with an actuating tool and having a plurality of radially directed, vertical slots formed 60 therein; the bases of said slots being inclined inwardly and downwardly with respect to the vertical axis of the block, scraping blades slidably contained within said slots provided with vertical and horizontal scraping edges lying respectively without the periphery and below the lower face of the block and having their inner edges beveled to conform to the inclined bases of said slots and seated thereagainst, and yieldable 65 means for normally retaining the blades retracted within the slots of the block. 70

4. A carbon removing device of the character described comprising a block having a means thereon for connection with an actuating tool and having a plurality of vertical, radially directed slots formed therein; the bases of said slots being inclined inwardly and downwardly to the center of the block at its lower face, scraping blades 80 mounted slidably within said slots having vertical scraping edges extended beyond the periphery of the block and having horizontal scraping surfaces extending below the lower face thereof and having their inner edges 85 inclined in accordance with and seated against the bases of said slots, said blades also having apertures therein and a spring band extending about the block and through said apertures to yieldingly resist outward 90 movement of the blades. 95

Signed at Seattle, Washington, this 22nd day of November, 1920.

PETER B. SAUGEN.
